CLAIM

The ornamental design for a universal multi-plug adapter, as shown and described.

DESCRIPTION

FIG. 1 is a perspective view of a universal multi-plug adapter showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another top perspective view thereof; shown in another environment.

In the drawings, the broken lines are for the purpose of illustrating environment only and form no part of the claimed design.
